John Elgar.

The schedule referred to in this letter, I will now make part of the same, containing a description in the words of the late John Elgar himself, of his improvement in the rail road car.

To obtain a form and combination of substances that will, reduce the friction in the rubbing part of a Rail Way Car, at its lowest point, where the "friction wheel" is not used, I adopt the admirable plan of outside journals, introduced & patented by R. Vivian. The essential advantage of which is that the journals are reduced one third in diameter (of course the friction is equally reduced) still preserving the full size and strength of the axles between the wheels. The axles extend thro' the wheels about 14 $\frac{1}{2}$ inches, are steel'd and turned to 2 inches diameter and hardened which forms the journal. To this journal I adopt a bearing or box of cast iron, either in two pieces, or one entire piece and to obtain an opening in the box, that shall at once combine a proper shap'd fit the journal with a smooth and excessively hard surface it is cast upon a "chill", a piece of iron dredged to the size of the journal, but with three ribs upon it running lengthwise which divides the circular opening of the box into three parts, and reduces the bearing in the journal to $\frac{1}{4}$ of its circumference. In the contact of substances so hard this quantity of surface is sufficient and the friction is less. The back part of the box is at the same time chilled for the purpose of receiving against it the steel centre point of the journal, that the tendency to lateral motion may be governed without the friction consequent upon should'd. To exclude dust and confine the oil, I use a packing plate similar to that which is used at the piston stem of the Steam Engine, this plate rests on the journal in front of the box, and is secured to the latter with packing of hemp, leather & cork. The side or face of the plate toward the wheel has projecting flanges upon it which embrace the hub and exclude the air.

The box will perhaps contain one half gill of oil, beside the journal which ensures a perfect lubrication of the latter. The improvement that I claim as my invention, is the chilled cast iron box combined with the steel center pointed journal. The peculiar form of the inside of the box which reduces the surface of the bearing - and the Packing Plate. —
